ACTION FOR PLAYER PIANOS

Filed Nov. 12, 1924

Guillermo Freund
Emil Bönnelycke, Attorney

UNITED STATES PATENT OFFICE.

GUILLERMO FREUND, OF LIMA, PERU.

ACTION FOR PLAYER PIANOS.

Application filed November 12, 1924. Serial No. 749,524.

To all whom it may concern:

Be it known that I, GUILLERMO FREUND, a citizen of Peru, residing at Lima, Peru, have invented certain new and useful Improvements in Actions for Player Pianos, of which the following is a specification.

This invention relates to pneumatic actions for player pianos, and more particularly to actions of the type disclosed in my prior Patent No. 1,506,980, granted September 2, 1924.

According to the construction shown and described in said patent, an all-metal action chest is utilized, containing a set of valve boxes, one for each tracker duct, these boxes likewise being made entirely of metal. The valve disposed within each valve box is controlled from the corresponding tracker duct through the intermediary of a metal tube fixed to a supporting disk which is itself removably mounted in the front wall of the action chest; and this tube carries at its inner end a flexible diaphragm which directly actuates the aforesaid valve in a manner to open communication, through the valve box, between the chest and the associated striker pneumatic, with the result that the latter is collapsed by the vacuum existing in the chest and, in turn, operates the corresponding key action.

The present invention is essentially a development of the earlier construction, and its primary object is to simplify and otherwise improve the same while still preserving all of the original advantages. To this end, the new construction does away with the fixed tube and its adjuncts, and connects the tracker tube directly to the valve box—or, more properly, to a removable cap or sleeve of special form mounted in the top of the box. The latter is preferably cylindrical in shape, and is disposed exteriorly of and behind the action chest, with which latter it is removably coupled, so that it may be readily detached for cleaning or other purposes and, if necessary, replaced by a new part without difficulty and at comparatively low cost.

It is of particular importance in the present construction that each individual striker pneumatic and the associated valve box are so arranged as to form a single unit which is supported by the action chest but is detachable bodily from the same, so that it may be readily disconnected at will and subsequently re-connected with equal facility.

Other and still further improvements and advantages are comprised in the invention and will become apparent in the course of the description which follows.

In the accompanying drawings:

Figure 1 is a side elevation, with parts in section, of the complete invention;

Fig. 2 is a side elevation of one of the removable units previously mentioned;

Fig. 3 is a perspective view of one of the valves;

Fig. 4 is a detail section of a slightly-modified form of valve box cap;

Fig. 5 is a plan view of a lug carried by the abstracts;

Fig. 6 is a bottom plan of the membrane and its disk.

Referring more particularly to the drawings, the action chest, as here shown, consists of a metal pipe 1, preferably made of brass, mounted horizontally in the instrument and having its interior connected with the usual vacuum-producing mechanism (not shown).

In the upper front portion of this pipe or chest there is formed a series of openings 2, at each of which is soldered one end of a short, horizontal metal tube 3 containing, intermediate its ends, a fixed collar or stop 4. A second tube 5, of the same diameter as the collar 4, is telescopically and removably inserted in tube 3 and abuts therein against the said collar, its other end being soldered in a third tube 6 of the same diameter as the first tube which, in turn, is soldered at an opening 6' in the upper part of a vertical metal cylinder 7 that constitutes the body of the valve box, as hereinafter fully described. The lengths of the several tubes are such that when the

free end of the coupling tube 5 engages the stop collar 4, the adjacent ends of the two main tubes 3 and 6 will likewise abut. An opening 9' is also formed in the cylinder 7 immediately below the opening 6' and has soldered at its edge the adjacent end of a tube 9 which, at its other end, is offset abruptly downward, as indicated at 10, this offset part 10 being secured in an opening 11' in the upper member of the striker pneumatic 11, the interior of the latter thus communicating with the lower portion of the valve box. As usual, there are a striker pneumatic and an associated valve box individual to each tracker duct, and the pneumatics are, or may be, of conventional type, and are disposed side by side.

The valve boxes 7 are connected with the action chest 1 and the pneumatics 11 by the tubing previously described, which, like the chest itself, is preferably constructed of brass; and since the members 3 of the upper tubing are rigidly secured to the chest 1, the latter thus serves as the means whereby the valve boxes and the pneumatics are supported. Furthermore, each valve box, the tubes 5, 6 and 9 secured thereto, and the pneumatic 11 to which the offset end 10 of tube 9 is affixed conjointly form a single unit which can be readily coupled to and uncoupled from the action chest for the purposes above stated, due to the removable telescopic engagement of the tubes 3 and 5; one such unit being illustrated in Fig. 2.

Each of the valve boxes comprises upper and lower removable caps 12 and 13 which are threaded into the box ends, the upper cap having an upstanding nipple 14, over which is fitted one end of a rubber or other flexible tube 15 that leads at its other end to a perforation or duct in the tracker, as usual. The aforesaid upper cap 12 is utilized as a support for a thin, flexible 45 diaphragm or membrane 16 which, in turn, has glued or otherwise secured to its under face a fiber disk 17, the latter and the membrane being provided with a tiny central opening or bleed 17'. In the form 50 shown in Fig. 4, the membrane is disposed immediately against the lower edge of the cap—which is designated 12'; but such one-piece construction may, if desired, be modified to the extent of securing the membrane 55 against the lower edge of a separate inner sleeve or ring 18 which is threaded into the neck of the cap 12 so that the ring and membrane may thus be detached from the cap. The lower cap 13 is in the nature of 60 an open sleeve or throat-piece to permit communication between the lower portion of the valve box and the atmosphere, the upper end 19 of this cap forming a valve seat. Suitable packing may be interposed 65 between both caps and the box ends, and

also between the ring 18 (if used) and cap 12, to provide air-tight joints thereat.

Intermediate its top and bottom, the valve box is provided with a horizontal partition 20 that divides its interior into upper, and lower chambers with which the compound upper tube 3—5—6 and the lower tube 9 respectively communicate. This partition has a central opening 21, the edge of which is turned down to form a valve seat 22; and between the seats 22 and 19 there is disposed a movable valve 23, the function of which is to rest against said seats alternately and thereby control communication between the striker pneumatic and the interior of the valve box—in other words, between said pneumatic and suction and atmosphere. The top and bottom portions of the valve are preferably made of layers of fibrous material so as to form tight joints with the respective valve seats, and the valve is further provided with a set of upstanding pins 24 which extend through the partition opening 21 so as to guide the valve during its movements but without obstructing the passage of air through said opening.

The parts, so far as now described, operate substantially as follows:—Due to the connection of the valve boxes with the action chest, in which a vacuum is maintained by the pump or other suction mechanism, such vacuum will be transmitted to said boxes and (assuming that all of the tracker ducts are closed by the note sheet) will exert an upward pull upon the valves 23, whereby the latter are raised against the upper valve seats 22; the bleeds 17' providing communication between the spaces above and below the membrane. This upward movement of the valves uncovers the valve seats 19 and, hence, connects the lower chambers of the valve boxes with atmosphere; said chambers, in turn, communicating with the striker pneumatics, which are thereby expanded. At the same time, communication between the chambers of the boxes is interrupted, due to the contact of the valves with the upper valve seats, this being the position of the parts at the moment when the movement of the note sheet commences.

Now as soon as a perforation in the note sheet is brought into registration with the corresponding duct in the tracker, air will be admitted to the connected tracker tube 15 and thence to the upper chamber of the respective valve box and will press down or expand the membrane 16 and its disk 17, thereby forcing valve 23 downward. The downward movement of said valve uncovers the opening 21 and closes the opening formed through seat 19, with the result that the lower chamber of the box and, consequently, the striker pneumatic which is in constant connection therewith, are cut off from at-

mospheric communication and brought into communication with suction—i. e., into communication with the action chest through the intermediary of the upper chamber of 5 the box and the compound tube 3—5—6. The pneumatic will thereupon be collapsed and, in its movement, will operate the respective key action. When the note-sheet perforation passes beyond the tracker duct, 10 conditions are again reversed, and the various parts return to their normal positions.

In order to enable the pneumatic, during its collapse, to operate the associated key action, the movable member thereof is designed 15 to lift a lateral projection or lug 25 (Fig. 5) fixed to the vertically-moving member or abstract 26 of the key action; such lug being preferably in the form of a flat, paddle-shaped element having a threaded 20 stem for engagement in a socket in the abstract, and the movable member of the pneumatic preferably carrying a longitudinal extension 27 terminating in a rounded felt pad or cushion 28 for direct engagement with 25 said lug.

According to my invention, and for the purpose of obtaining as nearly as possible a rectilinear movement of the abstracts 26, so as to insure thereby an accurate and correct 30 operation of the wippens 29 and their associated jacks 30, (which parts, as well as those directly comprising the hammer mechanism, may be of conventional type), I connect each abstract with the adjacent action 35 rail 31 by means of a parallel-motion device. Such connecting device, as here shown, consists of short upper and lower links or arms 32 which are pivoted at one end to bars 33 extending along the top and bottom edges of 40 the rail, and which, at the other end, project through and are pivotally secured in elongated openings 34 formed vertically through the abstract and rounded at top and bottom. This arrangement, as will be understood, 45 maintains the abstracts vertical throughout their movements and, furthermore, permits the usual pivotal connections between them and the wippens and the rockers to be dispensed with; the opposite ends of the abstracts being rounded in the present construction, as shown, and designed to loosely 50 contact with felt strips 35 and 36 which are secured, respectively, to the under faces of the wippens and the upper face of the frame or bed 37.

While I have illustrated what I now consider to be the preferred form of the invention, it is to be understood that no limitation to the precise details of the present disclosure is intended, as the invention is obviously susceptible of modifications and changes within its scope as claimed.

I claim as my invention:—

1. In a pneumatic action for player 65 pianos and the like, the combination, with

an action chest having a set of short tubes secured laterally to it at regularly-spaced intervals, of a set of operating units, one for each tube, readily attachable and detachable bodily and individually to and from 70 said chest; each unit comprising a valve box and a striker pneumatic, the valve box being provided with a pair of tubes which project laterally one above the other from the same side of the box, one tube of 75 the pair being removably and telescopically engaged with an action chest tube, and the other tube being connected to the pneumatic.

2. In a pneumatic action for player 80 pianos and the like, the combination, with an action chest having a set of short tubes secured laterally to it at regularly-spaced intervals, of a set of operating units, one for each tube, readily attachable and detachable bodily and individually to and from 85 said chest; each unit comprising a valve box and a striker pneumatic, the valve box being provided with a pair of tubes which project laterally one above the other 90 from the same side of the box, one tube of the pair being removably and telescopically engaged with an action chest tube, and the other tube being rigidly fastened to the pneumatic and constituting the sole support 95 therefor.

3. In a pneumatic action for player 100 pianos and the like, the combination, with an all-metal, tubular action chest provided at regular intervals with lateral metal tubes, 105 of a set of operating units, one for each tube, readily attachable and detachable bodily and individually to and from said chest; each unit comprising an all-metal valve box and a striker pneumatic, the valve 110 box having rigidly secured to it a pair of metal tubes, one of which is removably connected to the corresponding action chest tube to support the valve box and, hence, the unit directly therefrom, and the other of which is connected to the pneumatic to support the same entirely from the valve box.

4. In a pneumatic action for player 115 pianos and the like, the combination with an all-metal, tubular action chest provided at regular intervals with lateral metal tubes, of a set of operating units, one for each tube, readily attachable and detachable bodily and individually to and from said chest; each unit comprising an all-metal valve box and a striker pneumatic, the valve box having rigidly secured to it a pair of metal tubes which project laterally one above the other from the same side of the box, one tube of 120 the pair being removably and telescopically engaged with the corresponding action chest tube to support the valve box and, hence, the unit directly therefrom, and the other tube being rigidly fastened to the 125 130

4
pneumatic and constituting the sole support therefor.

5. A pneumatic action for player pianos and the like, comprising an all-metal tubular action chest provided at regular intervals with lateral metal tubes; an all-metal valve box individual to each tube and having a pair of metal tubes rigidly secured to it; and a striker pneumatic individual

to each valve box and to which one tube 10 of the pair on the valve box is rigidly fastened, the other tube of the pair being telescopically engaged with, and readily removable from the corresponding action chest tube.

15 In testimony whereof I affix my signature.

GUILLERMO FREUND.
